US00D672107S

(12) **United States Design Patent**
Van Landingham, Jr. et al.

(10) **Patent No.:** **US D672,107 S**
(45) **Date of Patent:** **** Dec. 4, 2012**

(54) **MOP FRAME**

(75) Inventors: **Alfred Reneau Van Landingham, Jr.,**
Winchester, VA (US); **Jesse Andrew**
Matola, Winchester, VA (US)

(73) Assignee: **Rubbermaid Commercial Products,**
LLC, Winchester, VA (US)

(**) Term: **14 Years**

(21) Appl. No.: **29/405,784**

(22) Filed: **Nov. 7, 2011**

(51) **LOC (9) Cl. 04-01**

(52) **U.S. Cl. D32/50**

(58) **Field of Classification Search** D32/50,
D32/51, 39-45; 15/116.1, 116.2, 119.2,
15/147.1, 147.2, 150, 208, 209.1, 210.1,
15/228; 401/137-140; 210/767

See application file for complete search history.

(57) **CLAIM**

We claim the ornamental design for a mop frame, as shown and described.

DESCRIPTION

FIG. 1 is a front view showing our new design for a mop frame;

FIG. 2 is a back side view showing our new design shown in FIG. 1;

FIG. 3 is a right side view showing our new design shown in FIG. 1;

FIG. 4 is a left view showing our new design shown in FIG. 1;

FIG. 5 is a perspective view showing our new design shown in FIG. 1;

FIG. 6 is a top view showing our new design shown in FIG. 1; and,

FIG. 7 is a bottom view showing our new design shown in FIG. 1.

The portions shown in broken lines are not part of the claimed design but show the environment in which the design is associated.

1 Claim, 7 Drawing Sheets
